MACHINE FOR CLEANING SEEDS

Robert R. Freund, Denver, Colo.

Application January 28, 1935, Serial No. 3,797

5 Claims. (Cl. 209—114)

This invention relates to improvements in that class of machines used for cleaning seeds and more particularly leguminous seeds, such as beans and peas, by separating them from particles of dirt, stones and other foreign matter.

It is an object of this invention to produce a machine of simple and substantial construction that will have a large capacity and which will effectively remove all irregularly shaped particles of foreign matter as well as broken seeds.

Another object of this invention is to produce a machine of the type specified in which the cleaning device and the feeding device shall be interconnected so that the feed will be accurately proportioned to the cleaning capacity of the machine.

A still further object of this invention is to produce a machine of such construction that the capacity, at a given speed, can be changed so as to make the same machine suitable for different sized jobs.

Another and further object of this invention is to produce a machine having a horizontal movable table or belt instead of an inclined one.

The above and other objects that may become apparent as this description proceeds, are attained by means of a construction and an arrangement of parts that will now be described in detail and for this purpose, reference will now be had to the accompanying drawings in which the machine has been illustrated in its preferred form and in which—

Figure 1 is a top plan view of the machine;

Figure 2 is a side elevation of the machine shown in Figure 1;

Figure 3 is a cross section taken on line 3—3, Figure 1, and shows the feed hopper and feed roll in section;

Figure 4 is a section taken on line 4—4, Figure 1;

Figure 5 is a section taken on line 5—5, Figure 1, and shows the discharge for the cleaned materials and for the matter separated;

Figure 6 is a fragmentary section, similar to that shown in Figure 4, and illustrates the position of the parts when an irregularly shaped body passes one of the flexible wipers;

Figure 7 is a fragmentary end elevation showing a slight modification;

Figure 8 is a fragmentary side elevation showing a slightly modified form of the wiper;

Figure 9 is a top plan view of a modified form of the machine;

Figure 10 is a side elevation of the machine shown in Figure 9, and

Figure 11 is a fragmentary section showing the feed device to a somewhat enlarged scale.

In the following description, similar reference characters will be used to designate similar parts in the several views.

The machine comprises a frame whose function is to support the several parts of the machine and which comprises a plurality of posts 1 connected by longitudinally extending bars 2 and 3. The tops of the posts are connected by transversely extending angles 4 that in turn are connected by two slotted guide bars 5. The bars 3 serve as supports for two pairs of bearings 6 and 7 in which are journalled the shafts 8 and 9 respectively. The shafts are provided with rollers 10 that carry an endless belt 11, preferably of rubber composition, whose upper surface is provided with parallel ribs 12. A metal plate 13 is suitably supported by the frame in such a way that the plane of its upper surface is tangent to the upper outer surfaces of the rollers. The upper surface of plate 13 serves as a support for the belt which is thereby prevented from sagging.

A motor 14 is supported on a base 15, carried on a suitable support 16 and is provided with a pulley 17 with which a belt 18 is operatively connected. The belt 18 cooperates with the larger of a double reducing pulley 19, that is supported for rotation, on bar 3, by suitable means. Shaft 8 is provided with a pulley 20 that is connected with the smaller of the reducing pulleys 19 by a belt 21. The motor rotates in such a direction that the top of the belt moves from left to right when viewed as in Figures 1 and 2.

Shaft 9 is provided at one end with a bevel pinion 22 that meshes with a similar pinion 23 carried on the shaft 24, which shaft is mounted for rotation in bearings 25 and 26, and carries a pulley 27 from which a feed mechanism is driven by means of the belt 28.

The feed mechanism consists of an elongated hopper having an inclined side wall 29 and an opposed vertical side wall 30. The hopper is supported by members 31 and 32 of which a number are provided. The hopper has permanent ends 33, and a removable partition 33a. The two sides 29 and 30 terminate short of the apex of the triangular ends 33, and the lower edge of side 29 is provided with a flexible strip 34 that forms an extension of its width. A feed roller 35 is located between the lower edge of side 29 and the roller 35 and the latter is provided with longitudinally extending grooves 55

36. Roller 35 is carried on a shaft 37 that is mounted for rotation in bearings 38 and has one end provided with a pulley 39 with which the belt 28 cooperates. Attention is directed at this 5 point to the fact that a positive feed mechanism is used and that it is driven from shaft 9 wherefore the feed is varied directly as the speed of the belt and after the parts have been properly adjusted so as to obtain the proper proportion 10 or relation between the feed and the speed of the belt, this will remain the same for all speeds.

Supported from the slotted bars 5 are a number 15 of wipers, each consisting of an angle bar 40, of a cross section like that shown in Figures 4 and 6. Bars 40 are each provided with a horizontal flange 41 and a vertical flange 42 of which the flange 42 is the thicker, and is preferably grooved for the reception of a flexible 20 resilient strip 43, which is preferably of rubber, but which may be of any other suitable material. Flanges 41 are each provided with two threaded 25 holes for the reception of the supporting bolts 44 which project through the slots in the supporting bars 5 and have large heads 45 that rest on the upper surface of these bars. The angle bars 40 are arranged diagonally of the belt in the manner shown in Figure 1, and are arranged in groups, each of which, preferably, 30 contains four bars, but a greater or less number may be used as may be found desirable. The bars 40 are adjusted by means of the bolts 44, so that the lower edges of the wiper strips 43 come very near, but do not touch the tops of 35 the ribs 12. After the bars 40 have been properly positioned as to height, the lock nuts 46 are tightened, so as to prevent accidental disturbance of this adjustment, and after the bars have been properly positioned along the supports 5, the nuts 47 are tightened to prevent 40 accidental disturbance of this adjustment. The bars are inclined with respect to the travel of the belt in the manner shown in Figure 1.

At the right (Figures 1 and 2) of each group 45 of wiper bars, a metal scraper bar 48 is provided. The scraper bars are preferably made of steel and are each provided with two bolts 49 whose upper ends are threaded and which project through the slots in the supports 5, and 50 are each provided with a nut 50, and may also have lock nuts, which have not been shown. Springs 51 are carried by the bolts 49 and are located between the tops of the scraper bars and the bottoms of bars 5 as shown in Figures 4 55 and 5.

In Figure 7, a slightly modified form of scraper bar has been shown. Bar 48a, instead of being vertical, as bars 48, is inclined in the manner shown, and is provided with two supporting bolts 49a, which are clamped in adjusted positions by means of the nuts 52.

Located over the last wiper bar of each group and the corresponding scraper bar is a bent plate 53. These plates comprise two flat surfaces, and are bent as shown in Figure 4, so as to have what may be termed a "gable" shape or form. Any seeds, such as peas or beans, that are deposited by the feeder onto the plates 53 will be divided between the two corresponding 65 groups of wipers in a manner quite apparent from an inspection of Figure 1.

An inclined metal plate or board 54 is arranged along the discharge edge of the belt 11 and has its upper edge 55 projecting underneath the plate 13 as shown in Figure 5. Plate 54 ex-

tends over a conveyor comprising a belt 56 that is driven from a pulley secured to one end of shaft 9. The conveyor belt passes over pulleys 58, 59 and 60, and moves in the direction of the arrow in Figure 2.

The cleaned seeds are carried on the belt 56 and are discharged at the right hand end of the conveyor (Figures 1 and 2). Troughs 57 are located under the discharge from each scraper 10 48, and extend over the conveyor 56 and discharge their contents into the box 61.

In Figure 8, a slight modification has been shown. In this view the wipers 43a have been 15 shown as provided with notches 62 which makes them yield more readily than when they are unnotched, as in the other views.

The operation of the machine described above and illustrated in Figures 1 to 8 is as follows: With the parts properly adjusted, the seed, (usually peas or beans) which have first been 20 screened so as to remove all foreign matter that is below a certain size, are placed in the hopper. The motor is now started, and the belt 11 begins to move. Seeds are discharged by the feed mechanism onto the belt and when the seeds 25 come in contact with the wipers 43, they are made to roll along these and are finally discharged onto the plate 54 and delivered to the conveyor 56. At this point, attention is called 30 to the fact that the upper surface of plate 13 and the corresponding surface of the belt 11 are horizontal, as distinguished from some similar machines of the prior art, in which the belts are inclined either transversely or longitudinally, or both.

The feed is so adjusted that after the machine 35 has got fairly started, a single row of seeds will lie along each wiper.

Since the seeds are smooth and substantially 40 round, they will roll on the ribbed belt while the foreign matter, such as pieces of rock, vegetable matter, etc., are usually of irregular shape, and will not roll, but will be caught by the ribs 12, and passed underneath the wipers 43 in the manner shown in Figure 6. When the 45 foreign matter reaches the scraper bar or bars 48, it will be dislodged from its position on the belt and moved towards the discharge side thereof, and will finally be discharged into a trough 57. If a rock is so attached to the belt 50 that it will not be dislodged and moved sidewise by the scraper bar, the latter will raise and let it pass underneath, and it is for this purpose that the scraper bars are so mounted that they can move up from normal position when occasion 55 requires. If scraper bars like those shown in Figure 7 are employed, the inclination of the scrapers is depended on to dislodge the rock or other foreign matter.

As many groups of wiper bars and scrapers 60 can be used as may be found desirable, and by removing the partition 33a, another group can be added to the machine illustrated in Figures 1 and 2.

In Figures 9, 10 and 11, a modified form of 65 the invention has been shown, in which a plate 13a, of circular shape, is mounted for rotation in its own plane, and about a vertical axis. The endless belt is replaced by a circular rubber sheet 11a which is provided on its upper surface 70 with radial ribs 12a.

Supported above the rotating table are two concentric rings 5a to which the wiper bars 40a are secured. Scraper bars 48a are supported from the rings 5a, one scraper for each group 75

of wiper bars. The shaft 63, to which the plate 13a is attached, is rotated from a suitable source of power by the belt 64. A hopper 65 is located above the rotating table and is provided with an opening 66 in its bottom for each group of wiper bars and scrapers. Pipes 67 extend from the openings 66 to points near the inner ends of the first wiper bar of each group. The discharge ends of pipes 67 are provided with tubular rubber extensions 68 that terminate close to the tops of the ribs 12a; the seeds will be fed from the tubes 68 only when the table rotates. A circular hopper whose cylindrical wall has been designated by numeral 69, is so located that it will receive the seeds discharged from the table, and a trough 51a is located at the discharge end of each scraper 40a, to carry the foreign particles beyond wall 69, and into the trough 70. The seeds are removed from hopper 69 through openings 71.

The operation of the modified machine is substantially the same as that already described in connection with the preferred form, and will therefore not be described in detail. In some cases it may be preferable to employ a round rotating table, in which case the construction shown in Figures 9 and 10 can be used.

It is evident that by inclining the wipers and the scraper in the opposite direction with respect to a concentric circle representing the locus of a point on the moving table so that the ribs will first intersect the line of the wipers near the outer circumference of the table and then depositing the seed near the outside of the circular table the latter will move inwardly towards the center.

Attention is called to the following features of the construction that are considered to be of particular importance and which are believed to be novel.

In the first place, the belt 11 and the corresponding element 11a in the modified form, move in a horizontal plane as distinguished from an inclined one, as it has been found that by this construction, no movement of the seeds takes place, except that caused by the action of the wipers. The belt has its upper surface provided with parallel ribs of less height than the minimum dimensions of the seeds, and these facilitate the transverse movement of the seeds, and the retention of the foreign matter. The feed is controlled by the speed of the belt or the table so as to give the optimum rate of feed at all speeds. The wipers are arranged in groups and each set has a scraper, and in this way, a large capacity can be obtained in comparison with the size of the machine. The wipers are adjustable as to height, and the scrapers are so mounted that tearing away of the ribs (12, 12a) will be prevented.

Having described the invention, what is claimed is:

1. A machine of the character described, comprising in combination with a travelling carrier belt, a group of spaced, substantially parallel wipers extending transversely thereof in a direction oblique to the direction of movement of the belt, a scraper bar associated with the group of wipers, a source of leguminous seeds, means for feeding the seeds from said source onto the carrier, along one edge thereof and means for shielding the space between the last wiper and the adjacent scraper bar from the feed.

2. A machine for cleaning leguminous seeds

comprising in combination a movable carrier-member, a hopper located along one side of the member, an elongated fluted feed roller in the bottom of the hopper and means for turning the feed roller at a speed proportional to the speed of the carrier-member, so as to produce an elongated line of feed, a plurality of flexible wipers located above the carrier-member, and forming a group, a scraper bar located at the rear of each group, said wipers and scraper bar extending across the line of feed and obliquely to the direction of movement of the carrier, and means for shielding the space between the last wiper and the scraper from the feed.

3. A bean-cleaning machine comprising in combination, a horizontal movable separating member whose upper surface is provided with spaced ribs that extend in a direction transverse of the direction of movement, a group of substantially parallel, spaced wipers located above the separating member and inclined with respect to the direction of movement thereof, a scraper bar positioned at the end of the group of wipers, the scraper bar being mounted for movement in a vertical direction, means for limiting its downward movement, and means operated by the movement of the separating member for feeding seeds onto the surface thereof along the part thereof where the transverse ribs first intersect the lines of the wipers.

4. A machine for separating leguminous seeds from foreign matter comprising, in combination, an endless traveling belt whose upper surface is horizontal, the upper surface of the belt having transversely extending spaced ribs whose height is less than the minimum dimension of the seeds, means operated by the movement of the belt for feeding seed onto the belt along one side thereof, a group of wipers positioned over the belt and inclined with respect thereto in such a way that a line perpendicular to the center line of the traveling belt will first intersect the lines of the wipers at the side of the feed whereby when the belt moves, the seeds will move toward the opposite side of the belt, and a scraper bar positioned at the end of the group of wipers, said bar being of metal and located so as to be substantially parallel to the wiper bars, the scraper bar being mounted for limited movement toward and away from the separating surface.

5. A machine for separating irregularly shaped particles of foreign matter from pulse seed, comprising in combination, a supporting frame, an endless belt carried by the frame and so positioned that its upper surface is horizontal, the outer surface of the belt having spaced parallel ribs of less height than the minimum dimension of the seeds, a pair of supporting bars located above the belt, a plurality of wiper bars adjustably attached to the supporting bars, the wiper bars having strips of flexible material attached thereto, the lower edges of the strips terminating close to the tops of the ribs, a metal scraper bar located behind the wiper bar, means for connecting the scraper bar to the supporting bar for limited vertical movement, the wiper and scraper bars being inclined with respect to the direction of travel of the belt, and means for feeding seed onto the belt in front of the wiper bar, and at the side of the belt where the transverse ribs first intersect the line of the wiper bar.

ROBERT R. FREUND.
